Primary Examiner — Ian Simmons*Assistant Examiner* — Shannon Morgan(74) *Attorney, Agent, or Firm* — Muncy, Geissler, Olds & Lowe, P.C.**CLAIM**

The ornamental design for a display screen with graphical user interface, as shown and described.

DESCRIPTION

FIG. 1 is a front view of a first embodiment of a display screen with graphical user interface showing my new design; and, FIG. 2 is a front view of a second embodiment of a display screen with graphical user interface showing my new design. The broken lines in the figures showing portions of the display screen and graphical user interface form no part of the claimed design.
